UNITED STATES PATENT OFFICE.

ABRAHAM G. FELDMAN, OF CHICAGO, ILLINOIS.

CRIB.

Application filed December 24, 1925. Serial No. 77,589.

This invention relates to cribs and more particularly to a means to secure one or both of the sides thereof in position.

Briefly stated, an important object of the invention is to provide a locking means for one or both of the sides of a crib which normally holds the side in a fixed or adjusted position and which may be operated either by the foot or the hand of the operator for releasing the locking means to either raise or lower the side in a highly convenient and expeditious manner.

A further and equally important object is to provide a locking means for the sides of a crib which while highly accessible to an operator is practically inaccessible to the occupant and which will not be exposed to the view of the occupant so there will be no temptation to play with the locking means and possibly bring about the accidental descent of the side of the crib.

Another object of the invention is to provide a frictional yet noiseless locking means for one or both of the sides of a crib which is positioned at the bottom of the sides so that the same is inconspicuous and so that any scratches which the same may cause will not be conspicuous.

Other objects and advantages will be apparent during the course of the following description.

In the accompanying drawings forming a part of this application and in which like numerals are employed to designate like parts throughout the same:

Figure 1 is a perspective of the improved crib locking means applied;

Figure 2 is a side elevation of a crib equipped on one side with the improved locking means, the vertically movable side being shown in full lines in its elevated position and in dotted lines in its lowered position;

Figure 3 is a perspective view on an enlarged scale of the improved locking means applied;

Figure 4 is a perspective of a brake shoe and attaching means therefor;

Figure 5 is a fragmentary side elevation illustrating the locking means applied, the brake shoe and the guiding means therefor being shown in section; Figure 6 is a view similar to Figure 5 showing the locking means released.

In the drawings, wherein for the purpose of illustration is shown a preferred embodiment of the invention, the numerals 5 design-

ate the posts of a crib and the numerals 6 designate guide rods carried by the posts and having their major portions spaced therefrom so that the terminals of the vertically movable side 7 may slide thereon, this feature being clearly shown in Figure 1.

The invention forming the subject matter of this application consists of a means for locking the side 7 in a fixed position and for releasing the same in a highly convenient and expeditious manner and by reference to Figure 3 it will be seen a brake shoe 8 of U-shaped formation is provided with a transversely curved bight portion about which a friction member 9 is extended for frictional contact with the adjacent guide rod 6. Of course, the friction member 9 may be of rubber or the like and when pressed into contact with the rod 6 one side of the bed or crib will be locked in position, all of which will be fully described. However, at this point it might be stated that the brake shoe is held in position for frictional engagement with the rod 6 by means of a U-shaped guide 10, the upper and lower portions of which have ears or attaching loops 11 arranged above and below the brake shoe and receiving the rod 6.

In carrying out the invention each shoe 8 is provided with a pair of ears 14 to which the outer terminal of the downwardly projecting branch of a main actuating lever 16 is pivotally connected. The lever 16 is connected at the juncture of its branches to a hanger 17 attached to the bottom rail of the side of the crib by an attaching bolt 18 and by barbs or teeth 19. The teeth 19 are forced into the bottom of the bottom rail so as to hold the hanger 17 against turning. A suitable pivot element 20 connects the lever 16 to the depending ears of the hanger 17 so that the lever may be freely rocked.

Figure 2 plainly illustrates that the side 7 of the crib carries two levers and the inner portions of the two levers carried by the sides are received in a connecting member 26 of channeled or tubular formation. The connecting member 26 has longitudinal slots 27 for the reception of connecting pins 28 by means of which the inner portions of the levers are held in place. It is believed to be obvious that the connecting member 26 is adapted to be moved vertically by the operator and the provision of the sliding connection between the levers and the connecting member avoids binding.

When the crib is equipped with the locking

device as shown in Figure 2 the weight of the connecting member 26 and the inner portions of the levers will tend to move the friction members 9 upwardly and outwardly into binding engagement with the rods 6. Also the weight of the side 7 will be transmitted through the friction members 9 to the rods 6 so that the side is firmly held in place. However, when it is desired to drop the side 7 it is merely necessary for the operator to move the connecting member 26 upwardly whereby the friction members 9 are moved inwardly out of binding engagement with the rods 6. The side 7 is now released and may be lowered to the desired position.

Figure 3 plainly illustrates that the sides of the connecting members 26 are provided with longitudinally curved flanges 30 for engagement by the toe of the operator. If it is desired to drop the side 7 without the aid of the hands it is merely necessary to move the toe upwardly into engagement with the flanges 30 and hold the toe in engagement with these flanges during the descent of the side 7. There is nothing, however, to prevent the free use of the hands in lowering the sides of the crib. In carrying out the invention, the levers 16 may be held in inoperative positions by a pair of spring clips 33 of U-shaped formation and these spring clips are secured as shown in Figure 3 to the under side of the bottom rails of the sides 7. When the inner portions of the levers 16 are engaged by the clips 33 the inner portions of the levers will be held in elevated positions and the friction members 9 will be held in inoperative positions. The spring clips 33 are thus useful when it is desired to raise and lower the side 7 without the continued aid of the foot of the operator, a light tap of the toe sufficing to seat the levers 16 in the clips 33, so that the side of the crib drops at once and without impediment or further aid.

With reference to the foregoing description taken in connection with the accompanying drawings it will be seen that the crib side may be lowered by one foot of the operator and that when it is desired to raise the side it is merely necessary for the operator to grasp the top rail or one of the stiles and lift the side to the proper position. In the instance where the clip 33 is furnished, a light tap with the foot upon the flange to drop the levers 16 out of the clips is necessary before the side of the crib is raised, so that the same may lock in elevated position when released by the hand.

As stated in the objects of the invention, the locking device is not exposed to the view of the occupant and consequently there is no temptation on the part of the occupant to play with the same and possibly bring about

the accidental descent of the side. As the locking device is entirely at the bottom of the side 7 any scratches caused by the guide member 10 will be inconspicuous. Also, it will be noted that the operating mechanism is carried solely by the side of the crib and not by the bed or ends thereof, making the installation simple and eliminating releasing devices or other expedients to render the side movable. The bed and ends may thus be designed in any style consistent with the positions of the guide rods 6. It will further be noted that the locking action is caused by the frictional engagement with the guide rods of a rubber element, which is in the nature of a cushion and operates without noise. The locking element may, of course, be made of any other material than rubber having equivalent properties for the present purpose.

Having thus described the invention, what is claimed is:

1. The combination with a crib having vertical rods and a side adapted to be raised and lowered along said rods, of arched levers rockably suspended from said side, brake shoes connected to the outer portions of said levers and adapted for braking engagement with said rods, a connecting member receiving the inner portions of said levers, and straps straddling said brake shoes and perforated to receive said rods to guide and retain said brake shoes in working relation to said rods.

2. The combination with a crib having vertical rods and a side adapted to be raised and lowered along said rods, of arched levers rockably suspended from said side, brake shoes connected to the outer portions of said levers and adapted for braking engagement with said rods when the levers are rocked to lower their inner portions and raise their outer portions, a connecting member receiving such inner portions, and clips on said side to receive and hold said inner portions when raised.

3. The combination with a crib having vertical rods and a side adapted to be raised and lowered along said rods; of a substantially U-shaped guide member, each arm thereof having free sliding engagement with a rod to dispose the bend laterally of the rod in spaced relation; a brake member retained between said guide arms and adapted for movement between said rod and bend of the guide; flanges on said brake member and extending beyond said guide in substantially parallel relation on opposite sides thereof; and brake member operating means carried by said side and connected with said flanges for moving said brake member between said rod and bend of the guide.

In testimony whereof I affix my signature.

ABRAHAM G. FELDMAN.
